UNITED STATES PATENT OFFICE.

HARVEY EVERETT AND LOUIS H. KURTH, OF LEWISTON, IDAHO.

FRUIT-PICKER.

1,099,289.

Specification of Letters Patent.

Patented June 9, 1914.

Application filed July 31, 1913. Serial No. 782,266.

To all whom it may concern:

Be it known that we, HARVEY EVERETT and LOUIS H. KURTH, citizens of the United States, residing at Lewiston, in the county 5 of Nez Perce and State of Idaho, have invented certain new and useful Improvements in Fruit-Pickers, of which the following is a specification, reference being had to the accompanying drawings.

- 10 This invention relates to certain improvements in fruit pickers and the object of the invention is to provide a device of this general character of a simple and comparatively inexpensive nature having means of a novel 15 and improved character whereby the fruit after being picked is permitted to fall or drop in such a manner as to effectively guard against the same becoming bruised or otherwise injured.
- 20 The invention consists in the details of construction and in the combination and arrangement of the several parts whereby certain important advantages are attained and the device is rendered simpler, less expensive 25 and otherwise more convenient and advantageous for use, all as will be hereinafter more fully set forth.

The novel features of the invention will be carefully defined in the appended claims.

30 In order that our invention may be the better understood, we will now proceed to describe the same with reference to the accompanying drawings, wherein—

Figure 1 is a side elevation of the device 35 partly in section; Fig. 2 is an enlarged fragmentary elevation of the upper end of the device partly in section; Fig. 3 is a perspective view of one pair of the levers; Fig. 4 is a section on the line 4—4 of Fig. 2; and Fig. 40 5 is a section on the line 5—5 of Fig. 2.

Referring more particularly to the drawing, the numeral 1 designates a pole which may be of any desired length, and connected to the pole at intervals along its length are 45 a plurality of clamping members 2. The clamping members are preferably formed of plates of spring metal, the intermediate portions of which are curved to form loops 3, the ends of the plates being bowed outwardly as at 4, for engagement with the pole, and the extremities of the plates extending in parallel relation for the reception of bolts 5 whereby the clamping members are securely fastened to the pole. Extending 50 outwardly from each loop 3 is a pin 6, and pivotally connected intermediate of their

ends to each pin is a pair of levers 7. The upper ends of each pair of levers diverge as at 8, and to normally maintain the diverging ends of the levers outwardly, V-shaped 60 springs 9 are connected at their opposite ends to the inner faces of the diverging portions of the levers. Outwardly extending nippers or arms 10 are connected to the extremities of each pair of levers 7, the nippers 65 on the upper ends of the levers being normally maintained in open position, while the nippers on the lower ends of the levers are closed. A chute 11 of canvas or other suitable material is connected to the nippers 70 by stitching or in any other desired manner, the chute being disposed between the pairs of nippers so that the portions of the chute between the nippers on the lower ends of each pair of levers are contracted, while 75 the portions of the chute between the nippers on the upper ends of the levers are maintained in expanded position.

Slidably disposed in the loops 3 of the clamping members is an operating rod 12, and connected at intervals along the length 80 of the rod are a plurality of outwardly extending rings 13, one ring being disposed around the diverging portions of each pair of levers so that upon upward movement of 85 the rod 12, the upper ends of the levers are closed and the lower ends thereof opened. Connected to the upper ends of the upper pair of levers 7 are a pair of laterally extending vertically disposed severing devices 90 14 which are preferably composed of circular rims to which gauze or some other flexible material is secured, allowance being made for slackness, so that when the fruit is grabbed by these devices it will yield to the 95 pressure of the parts when they come together, thereby allowing the fruit to fall down into the chute when the latter is open. If desired, a metal tubing 15 may be connected to the pole 1 to surround the upper 100 end of the chute, so that when the device is in position to pick fruit from the tops of trees, twigs and branches will be prevented from interfering with the operation of the nippers and will also be prevented from 105 piercing the chute.

In the practical use of our device, the pole is held in elevated position, so that the fruit which it is desired to pick is disposed between the plucking devices 14, and 110 upon upward movement of the operating rod 12, it will be seen that the disks or

circular rims 14 will be closed one upon the other so as to inclose the fruit between and within the gauze coverings which are connected to said rims, whereupon by pulling 5 downwardly upon the pole, the fruit is severed from the tree. Upon a downward movement of the operating rod 12, the plucking devices 14 will be separated, and the nippers 10 on the lower ends of the 10 upper pair of levers 7 will be closed, thereby allowing the fruit to fall from the plucking devices into the chute. The passage of fruit through the chute will be stopped by the contracted portions thereof, owing to the 15 closing of the nippers upon the lower ends of the upper pair of levers. In this position, the plucking devices are open for engagement with another fruit and upon upward movement of the lever 12 to close the 20 plucking devices about the fruit, the nippers 10 upon the lower ends of the upper levers 7 are opened to allow the fruit supported thereupon to fall upon the upper nippers 10 of the pair of levers disposed 25 directly below the upper pair of levers. It will be seen that upon repeated operations of the operating rod 12, the fruit within the chute will be allowed to gradually or intermittently pass therethrough out of the 30 lower end thereof into any suitable receptacle.

What we claim is:

1. A device of the character described comprising a pole, a flexible chute, pairs 35 of pivotally connected levers carried by said pole, the upper ends of said levers normally diverging from each other, outwardly extending nippers carried by the opposite ends of said levers and surrounding said chute, and means for closing the nippers on one end of said levers and opening the nippers on the other ends of said levers simultaneously, as and for the purpose described. 40

2. A device of the character described 45 comprising a pole, pairs of pivotally connected levers carried by said pole, the upper ends of said levers normally diverging from

each other, outwardly extending nippers connected to the opposite ends of said levers, a flexible chute carried within said nippers, 50 means for normally maintaining the diverging ends of said levers spaced from each other, and means for simultaneously closing the diverging ends of said levers, as and for the purpose described. 55

3. A device of the character described comprising a pole, pairs of pivotally connected levers carried by said pole, the upper ends of each pair of levers normally diverging from each other, outwardly extending 60 nippers connected to the opposite ends of said levers, a flexible chute carried within said nippers, an operating rod slidably connected to said pole, springs disposed between the diverging portions of each pair 65 of levers, and rings connected at intervals to said operating rod, said rings surrounding the diverging portions of said levers, as and for the purpose described.

4. A device of the class described, comprising a pole, pairs of pivotally connected levers carried by said pole, the upper ends of each pair of levers normally diverging from each other, outwardly extending nippers connected to the opposite ends of said 75 levers, a flexible chute carried within said nippers, an operating rod slidably connected to said pole, springs disposed between the diverging portions of each pair 80 of levers, rings connected at intervals to said operating rod, said rings surrounding the diverging portions of said levers and plucking devices connected to the upper ends of the upper pair of levers, said plucking devices comprising rims and flexible material connected to said rims. 85

In testimony whereof we hereunto affix our signatures in the presence of two witnesses.

HARVEY EVERETT.
LOUIS H. KURTH.
